FIG. 1
12

Inventor:
Edward E. Whitmore,
of Linthicum, Md. & Son
Atty.

UNITED STATES PATENT OFFICE.

EDWARD E. WHITMORE, OF CHICAGO, ILLINOIS, ASSIGNOR TO THE CURTAIN SUPPLY COMPANY, OF NEWARK, NEW JERSEY, A CORPORATION OF NEW JERSEY.

CAR-DIAPHRAGM.

1,078,758.

Specification of Letters Patent. Patented Nov. 18, 1913.

Application filed May 12, 1913. Serial No. 766,926.

To all whom it may concern:

Be it known that I, EDWARD E. WHITMORE, a citizen of the United States, residing at Chicago, in the county of Cook and State of Illinois, have invented certain new and useful Improvements in Car-Diaphragms, of which the following is a specification.

My invention relates more particularly to the accordion type of car vestibule diaphragms, and has for its object certain improvements in the manner of constructing and joining the leg and top portions, whereby to render the same more durable and efficient, and at the same time to greatly simplify and cheapen the cost of manufacture. The sections of such diaphragms, when so constructed that the plaits are joined along the inner meeting edges at an acute angle and by a seam or the like, are open to the objection that dust and cinders settle thereon and are by the rain carried into the space between the edges of the fabric cutting and rotting the same and effecting a speedy deterioration. Especially is this true of the top and shoulder portions which present conditions favorable to the lodgment of cinders and dust. It is comparatively easy to avoid this difficulty as to the top and as to the legs by forming such portions of each section of a single strip of fabric folded without creasing and seaming to form a trough of U-section, but difficulty is experienced in so joining the top and side portions at the shoulder as to present at this place a U-cross section without the employment of a number of flutings or darts which add greatly to the cost of manufacture and present pockets or obstructions to catch dust and permit the seepage of dirty water into the interstices.

According to the present invention, I attain the objects and avoid the difficulties outlined above, while materially reducing the cost of manufacture, by connecting the side and top portions of U-section by means of shoulder pieces in the nature of gussets formed of pieces having their outer edges curved and with darts in their ends whereby when inserted the outer edges of the strips forming the top and side portions are tangential to the arcuate outer edges of the gussets and the ends are joined on lines normal to the top and side strips, the gussets being free from any other overlapping joints and

the bottom of the gusset U extending in a straight line, at a pitch of substantially 45°, between the points of junction with the vertical and horizontal strips forming the side and top portions.

In order that the invention may be readily understood, preferred and modified embodiments of the same are set forth in the accompanying drawing and in the detail description predicated thereon. As, however, the invention is capable of embodiment in other and varied constructional forms, the drawing and description are to be construed in an illustrative rather than in an unnecessarily limiting sense.

In the drawing Figure 1 is an end elevation of a diaphragm with the face plate removed; Fig. 2 is a vertical section through the upper portion of the diaphragm; Fig. 3 is a detail of the gusset blank; Fig. 4 is a similar view of a modification; and Fig. 5 is a cross-section on the line 5—5 of Fig. 4.

The diaphragm, as shown, is composed of sections 11, 11 the outer edges of which overlie each other and are secured together by means of binding strips 12, the outer edges of the outer sections being secured one to the end of the car at 13 and the other to the face plate at 14 in the usual manner. The leg or side portions 15 of each section as also the top or roof portion 16 are composed each of a strip of fabric folded longitudinally without creasing to form a trough-like structure of U-cross section the bottom portion 17 of which is formed upon a gentle curve. Connecting the ends of the top portion 16 with the adjacent ends of the side portions 15 are shoulder pieces 18, 18 of similar U-cross section, the bottoms of which extend in a straight line between the points of junction with the top and side portions and at a pitch of substantially 45° as shown in Fig. 1. The shoulder pieces 18 are without longitudinal seams and preferably without transverse seams, the upper ends of the shoulder pieces underlying the ends of the top strip at 19 and overlying the ends of the side strips at 20 whereby to shed the water as it flows from the top or roof 16 over the shoulder and down the sides of the legs.

The outer meeting edges of the shoulder pieces of adjacent sections are formed upon an arc to which the corresponding edges of the side and top portions are tangent and

the line of junction between the shoulder piece and top and side strips are normal to such tangent lines.

In order to economize material and labor, 5 avoiding unnecessary disadvantageous seams and consequent necessary binding, I preferably form each of the shoulder pieces as a gusset, the outlines of which are shown in Fig. 3, the opposite outer edges 21, 21 being 10 curved upon an arc and the ends being provided with darts at 22, 22, the apices of which are in line with the longitudinal axis of the blank. When folded into U-shape the boundary lines of the darts coincide with the 15 lines of junction 19 and 20 between the gusset or shoulder piece and the top and bottom portions respectively of the diaphragm. Thus is formed a shoulder piece connecting the top and sides of the diaphragm which 20 presents an unbroken surface throughout its length, avoiding obstructions and simplifying the construction; the shoulder piece having the same advantageous U-section as the top and side portions and serving to carry 25 the water and dirt from the top of the diaphragm over the side without giving opportunity for seepage with its consequent destructive effect upon the diaphragm.

In order to utilize a narrower strip of material in the gusset, the same may be made in the way indicated in Figs. 4 and 5, the two pieces of material 18^a and 18^b having straight edges abutting along the line 23 without overlap and joined upon their under 30 side by a binding strip 24 breaking joints with the pieces 18^a and 18^b as clearly shown in said figures. The additional cost of the wider material, employed in the gusset shown in Fig. 3 is, however, more than compensated for by the saving of binding material and labor which is effected by forming the gusset in one piece.

By making the legs, top and corners of U-section, the expansibility of the diaphragm 45 as a whole is so greatly increased that a four-plait diaphragm has substantially the same capacity of expansion as a six-plait diaphragm of the V-section, whereby a saving of one-third in material and labor is 50 effected; moreover, the fold of the U-section not being a sharp one or along a well defined line the material is not cracked or broken by the constant working of the plaits, and the life of the diaphragm is thus greatly extended.

While the most advantageous results are secured by making the legs, top and shoulders all of U-section, yet it will be understood that as the legs are less liable to collect cinders and dust they may be made of V-section in combination with shoulder and top pieces of U-section; also that the corner or shoulder pieces having their bottoms extending in an unbroken straight line at substantially 55 45° may be employed to advan-

tage even where the V-section is retained in whole or in part. A further characteristic of the straight bottom shoulder piece is that, as the bottom is the shortest connecting line between the top and side pieces of the diaphragm, it defines the line of fold with U-plaits and thus causes the top and side pieces to fold along their longitudinal axes.

I claim:

1. In a car vestibule diaphragm of the accordion type, a section comprising side and top strips longitudinally folded to a U-cross section, and shoulder pieces of a similar cross-section connecting the side and top strips at the corners, substantially as described. 75

2. In a car vestibule diaphragm of the accordion type, a section comprising side and top strips longitudinally folded to a U-cross section, and one piece shoulder strips of a similar cross-section connecting the side and top strips at the corners, substantially as described. 85

3. A car vestibule diaphragm of the accordion type, each section comprising side and top strips and diagonal shoulder pieces all longitudinally folded to a U-cross section, the shoulder pieces joining the top with the side strips without intermediate overlapping joints and the bottom of the shoulder-U extending in a substantially straight line between the points of junction with the top and side strips, substantially as described. 90

4. A car vestibule diaphragm of the accordion type, each section comprising side and top strips and diagonal shoulder pieces all longitudinally folded to a U-cross section, the shoulder pieces joining the top with the side strips without intermediate overlapping joints and the bottom of the shoulder-U extending in a substantially straight line between the points of junction with the top and side strips, and at a pitch of substantially 45°, substantially as described. 100

5. A car vestibule diaphragm of the accordion type, each section comprising two side strips and a single top strip and two diagonal shoulder pieces all longitudinally folded to a U-cross section, the shoulder pieces joining the top with the side strips without intermediate overlapping joints, substantially as described. 115

6. A car vestibule diaphragm of the accordion type, each section comprising two side strips and a single top strip and two diagonal shoulder pieces all longitudinally folded to a U-cross section, the shoulder pieces joining the top with the side strips and the bottom of the shoulder-U extending in a straight line at a pitch of substantially 45° between the points of junction with the top and side strips, substantially as described. 120

7. A car vestibule diaphragm of the ac- 125

cordion type, each section comprising side and top strips and diagonal shoulder pieces all longitudinally folded to a U-cross section, the shoulder pieces joining the top with the side strips, the shoulder pieces formed of blanks having their outer edges curved and with darts in their ends whereby when inserted the outer edges of the side and top strips are tangential to the outer edges of the shoulder pieces and their ends are joined on lines substantially normal to such tangents, substantially as described.

8. A car vestibule diaphragm of the accordian type, each section comprising two 15 side strips and a single top strip and two diagonal shoulder pieces all longitudinally folded to a U-cross section, the shoulder pieces joining the top with the side strips without intermediate overlapping joints, the shoulder pieces formed of blanks having 20 their outer edges curved and with darts in their ends whereby when inserted in the diaphragm the outer edges of the side and top strips are tangential to the outer edges of the shoulder pieces and the U-trough of the shoulder pieces forms a continuation of the 25

U-trough of the side and top pieces, substantially as described.

9. A car vestibule diaphragm of the accordian type, each section comprising two 30 side strips and a single top strip and two diagonal shoulder pieces all longitudinally folded, the shoulder pieces joining the top with the side strips and the bottom of the shoulder extending in a straight line at a 35 pitch of substantially 45° between the points of junction with the top and side strips, substantially as described.

10. A car vestibule diaphragm of the accordian type, each section comprising two 40 side strips, a top strip, and two diagonal corner pieces joining said top with the side strips, said corner pieces being folded on a substantially straight line between the points of junction with the top and side 45 strips, substantially as described.

In witness whereof I have signed my name in the presence of two witnesses.
